UNITED STATES PATENT OFFICE

138,733

DESIGN FOR A MEMBERSHIP INSIGNIA DEVICE OR THE LIKE

Leon Pollack, Chicago, Ill., assignor to The National Mineral Company, Chicago, Ill., a corporation of Illinois

Application June 20, 1944, Serial No. 114,104

Term of patent 14 years

(Cl. D29—23)

To all whom it may concern:

Be it known that I, Leon Pollack, a citizen of the United States, residing at Chicago, in the county of Cook and State of Illinois, have invented a new, original, and ornamental Design for a Membership Insignia Device or the like, of which the following is a specification, reference being had to the accompanying drawing, forming part thereof.

Figure 1 is a face view of a membership insignia device or the like embodying the features of my new design.

Fig. 2 is an edge elevational view of the membership insignia device or the like shown in Fig. 1.

I claim:

The ornamental design for a membership insignia device or the like, substantially as shown.

LEON POLLACK.
